United States Patent Office

Des. 229,119
Patented Nov. 6, 1973

229,119

EYE SHADOW COMPACT

Garfield G. Litton, 1360 Ocean Parkway,
Brooklyn, N.Y. 11230

Filed May 5, 1972, Ser. No. 250,865

Term of patent 14 years

Int. Cl. D28—02

U.S. Cl. D86—10 G

FIG. 1 is a perspective view of an eye shadow compact showing my new design;

FIG. 2 is a front elevational view;

FIG. 3 is a top plan view;

FIG. 4 is a left end elevational view;

FIG. 5 is a right end elevational view;

FIG. 6 is an exploded perspective view; and

FIG. 7 is a right end elevational view of the applicator.

I claim:

The ornamental design for an eye shadow compact, substantially as shown and described.
